UNITED STATES PATENT OFFICE.

EBENEZER NYE HUTCHISON, OF CHARLOTTE, NORTH CAROLINA.

BRICK-KILN.

SPECIFICATION forming part of Letters Patent No. 252,319, dated January 17, 1882.
Application filed December 14, 1881. (No model.)

To all whom it may concern:

Be it known that I, E. NYE HUTCHISON, a citizen of the United States, residing at Charlotte, North Carolina, in the county of Mecklenburg and State of North Carolina, have invented certain new and useful Improvements in Brick-Kilns; and I do declare the following to be a full, clear, and exact description of the invention, such as will enable others skilled in the art to which it appertains to make and use the same, reference being had to the accompanying drawings, and to the letters or figures of reference marked thereon, which form a part of this specification.

15 My present invention is designed as an improvement on Letters Patent numbered 220,213, 7th October, 1879, and 246,997, 13th September, 1881, for kilns for burning brick; and to this end my invention consists in providing the air-supplying flues with perforated pipes for the admission of air to the fire-arches or combustion-chambers, and in the arrangement of said pipes so that air may be supplied or suppressed in any desired part of the kiln to promote or retard combustion, as may be found expedient or desirable.

20 Referring to the drawings, Figure 1 is a vertical longitudinal section on the line $x x$, Fig. 2. Fig. 2 is a horizontal sectional view on the line $y y$ of Fig. 1. Fig. 3 is a sectional view of a series of air-supplying perforated pipes, placed one within the other, for controlling the admission of air into any desired portion of the kiln.

25 A designates the fire-arches, which are by preference made to extend from one side of the kiln to the other; but, if desired, they may only extend to a fire-wall built across the center of the kiln.

30 B are the air flues or passages, which may or may not extend across the entire width of the kiln, and are provided with lateral openings C, which enter the fire-arches at intervals and at right angles thereto. This construction so far is substantially the same as the construction in the patents above referred to.

35 Within the air-flues, according to my present invention, I place perforated pipes D, the perforations registering with the lateral air flues or openings C. These perforated pipes may be made of clay, terra-cotta, or iron, or

other fire-resisting material, made in one piece or in sections, and extend throughout the entire width of the kiln, except where a fire or partition-wall is employed in the center of the kiln. These perforated pipes may, however, be placed under the fire-bed in the fire-arches, to promote combustion, as shown in dotted lines in Fig. 1.

40 For the more accurate and uniform burning of the brick, I employ a series of perforated air-pipes, one within the other, or any desired number nested or telescopically arranged, as shown in Fig. 3 and at A' in Fig. 2. The outer or larger one of these pipes, a, extends 45 inward a short distance—say one-third the width of the kiln or one-third the distance of the fire or partition wall. The next pipe, b, extends a short distance farther inward, while the next section, b', may extend to the opposite 50 side of the kiln, as shown at B, or to the wall or abutment in the center of the kiln, as shown at C', Fig. 2.

45 The advantages of this mode of construction are obvious, as it enables the operator to direct 55 the air-currents to the fuel at any desired point in the fire-arches, to increase or diminish the heat as may be desired, and insure a uniform 60 burning of the entire kiln, which is a very important consideration in view of the fact that in most of the devices now employed in burning brick many brick are too much burned, while many more are not burned enough, and are what is known as "salmon" bricks. By 65 closing up the opening between the pipes a and b at their outer ends the air will be conveyed or directed onto the fuel or products of combustion farther inward through the pipes b and b', and by closing up the passages or openings between the ends of the pipes b and b' the air will be conveyed by the pipes b further still into the kiln. A reverse order of closing the ends of the pipes will direct a greater amount of air to the larger or outer pipes and to the outer edges or sides of the kiln. If the natural draft is not sufficient, air may be supplied to all or to any desired number of pipes by a blower or other suitable device. The material which forms the sides of the fire-arches or air flues may be of iron, other metal, fire-clay, or other fire-resisting material, and constitute a permanent bench for the kiln, so that

the pipes will remain permanent. The kiln, however, may be built up as described in patents above referred to, the pipes being allowed to remain permanently in their places, and will 5 serve as guides for the building up of a new kiln, as they will determine by means of their perforations where the lateral flues are to be made and where the fire-arches are to be built, so that when once in position any common laborer 10 may construct a kiln as readily as a practical or professional kiln-builder.

Having thus described my invention, what I claim, and desire to secure by Letters Patent, is—

15 1. In a kiln for burning brick, the perforated pipes herein described, located within the side walls or in the bottoms of the fire arches, for supplying air to the fuel, as set forth.

2. In a kiln for burning brick and other analogous purposes, the perforated air-supply pipes 20 herein described, arranged one within the other, for directing and supplying air to any desired portion of the kiln, substantially in the manner and for the purpose set forth.

3. The method herein described of burning 25 brick uniformly, the same consisting in the application of air to the fuel to promote combustion at any desired point by means of perforated pipes of varying lengths, arranged one within the other, as set forth.

In testimony whereof I affix my signature in presence of two witnesses.

EBENEZER NYE HUTCHISON.
